UNITED STATES PATENT OFFICE.

ALFRED CROSSLEY, OF WASHINGTON, DISTRICT OF COLUMBIA.

PIEZO-ELECTRIC-CRYSTAL APPARATUS.

Application filed November 24, 1925. Serial No. 71,090.

To all whom it may concern:

Be it known that I, ALFRED CROSSLEY, a citizen of the United States, residing at Washington, District of Columbia, have invented certain new and useful Improvements in Piezo-Electric-Crystal Apparatus, of which the following is a specification.

My invention relates broadly to piezo electric crystal apparatus and more particularly to a mounting for piezo electric crystals employed for the constant frequency control of electrical circuits.

One of the objects of my invention is to provide a crystal holder by which piezo electric crystals may be hermetically sealed against moisture or gases which effect the proper oscillating characteristics of the piezo electric crystals.

Another object of my invention is to provide a piezo electric crystal mounting for connection in an electrical circuit whereby piezo electric crystals of different frequency characteristics may be readily inserted or removed from the electrical circuit for substituting piezo electric crystals of desired frequency characteristics for the control of electrical circuits at desired frequency.

Still another object of my invention is to provide a holder for piezo electric crystals comprising a housing in which the crystal is positioned and electrically connected to terminals extending exteriorly of the casing protecting the crystal from external foreign matter at the same time that the crystal is free to oscillate in its own natural period without hindrance.

My invention will be more fully understood from the specification hereinafter following by reference to the accompanying drawings, wherein:

Figure 1 is a perspective view illustrating the piezo electric crystal holder positioned in the mounting; Fig. 2 is a plan view showing the crystal holder positioned in its mounting; Fig. 3 is a partial cross-sectional view through the mounting and crystal holder showing the arrangement of the piezo electric crystal therein; and Fig. 4 is a front view of the piezo electric crystal holder.

The crystal holder of my invention has been used with low and high frequency crystals and has been found to meet requirements with reference to rated output and constancy of frequency. It has a very low capacity between terminals and is made to

permit quick change from one crystal to another where it is desired to control an electrical circuit at different frequencies. The crystal is mounted within an insulated housing where it is secured in position in such manner that substantially no mechanical pressure is placed upon the crystal so that it is free to vibrate in its own natural period. The electrical connections are brought out from the housing to cooperate with contacts mounted on the support upon which the crystal holder is positioned. The housing is provided with a lower plate which serves not only as an electrical connection for one side of the piezo electric crystal within the housing, but also as a guide for positioning the housing upon the main support. Referring to the drawings in more detail, the crystal holder is provided with a flat parallel metal plate 1 on which is secured by means of screws 1a, an insulated circular housing 2. The housing 2 is fitted with flat circular insulated cover 3 removably secured thereto by means of screws 3a. Between the cover 3 and the annular walls 2, a resilient gasket 4 is placed which hermetically seals the holder and thus excludes moisture or gases, which might effect the proper functioning of the piezo electric crystal 5, from the interior of the crystal holder. The piezo electric crystal 5 is held in place with its lower surface in contact with the top of plate 1 by means of metal pegs 6 or by an insulated washer member 80 which fits over the sides of the crystal and positively spaces the crystal in definite position with respect to the interior sides of the housing 2 without restricting movement of the piezo electric crystal 5. Upper metallic plate 7 lies in contact with the upper surface of the piezo electric crystal 5 and forms the upper contact for the crystal. This plate can be square, oblong or circular, conforming to the shape of the piezo electric crystal 5. The metallic plate 7 rests gently upon the top of the piezo electric crystal 5 to avoid any restriction in the inherent mechanical vibration of the crystal. In order to hold the plate 7 in a fixed position with respect to the top of the crystal, a small pin 8 is riveted to the center of the plate 7 and this pin is free to move vertically in an aperture 10 formed in a downwardly depending resilient guide member 9. The guide member 9 is secured to the under surface of the top of the housing

by means of a machine screw 14 and nut 12 and is so formed that it limits the upward movement of the top plate 7 to such an extent that the crystal will not jump clear of the retaining pegs 6 or spacing washer, if such washer is used. That is to say, the space above the piezo electric crystal defined by the lower surface of the resilient member 9 is so small that the 10 crystal cannot rise vertically to such an extent that it could pass over the retaining pegs 6. This precaution permits the crystal to remain in one fixed position and is therefore not affected by shocks and jars in 15 transportation or accidental falls or jarring. A flexible conductor is positioned between the head of the pin 8 and the guide member 9 for establishing electrical connection between the metallic head 14 and the resilient 20 spring member 19 which is secured at 20 to the insulating mounting 18.

The two terminals for the piezo electric crystal are the bottom plate 1 and the head 14 of the machine screw in the center of the 25 piezo electric crystal housing. By reason of the construction of the mounting 18, with bottom plate 15 secured thereto by means of screws 15^a, the crystal holder can be quickly attached or detached from the crystal 30 circuit. The bottom plate 15 is in the form of a metal guide having side portions 16 and 17 between which the bottom plate 1 of the housing 2 slides. The bottom plate 15 thereby contacts with the plate 1 and establishes 35 electrical connection with the lower surface of piezo electric crystal 5 from which a connection may be taken through guide portion 16, conducting strip 21 which is soldered thereto, the terminal post 22 and 40 the mounting 18 to the electrical circuit which it is desired to control in accordance with the constant frequency characteristics of the piezo electric crystal contained in the piezo electric crystal mounting.

45 A number of crystal holders in which crystals of different frequency characteristics are mounted may be provided and these holders slipped in or removed from the mounting in order to change from one crystal to another to secure control at different frequencies. This change can be made very quickly and I have successfully accomplished a change over nine different wavelengths 50 within a time of thirty (30) seconds. The piezo electric crystal is protected at all times 55 from moisture or gases which affect the proper functioning of the crystal by the hermetic closure illustrated.

60 It is not always necessary to hermetically seal the casing in which the piezo electric crystal is contained for the housing may be such as to offer a mechanical protection for the crystal and yet permit the free access of atmospheric pressure to the crystal.

65 I have shown the crystal holder circular

in shape, but it will be understood that other shapes may be imparted to the holder and that no limitations upon the invention are intended other than those imposed by the scope of the appended claims. 70

What I claim and desire to secure by Letters Patent of the United States is as follows:—

1. A piezo electric crystal holder comprising in combination a base plate, a housing 75 secured to said base plate, means for locating a piezo electric crystal centrally within said housing and contacting with said base plate, means for hermetically sealing said housing to atmosphere, and means for establishing electrical connection with the other side of said piezo electric crystal and a point exterior of said housing. 80

2. In a piezo electric crystal apparatus, 85 the combination of a mounting, a flat conductive base member arranged to detachably engage said mounting, a housing carried by said base member, a piezo electric crystal mounted in said housing with one side thereof engaging said conductive base member 90 and the other side thereof positioned in resilient electrical connection with a contact member external to said housing, and means carried by said mounting for resiliently engaging said contact member for 95 completing electrical connections with said piezo electric crystal.

3. A piezo electric crystal apparatus comprising in combination a mounting, a piezo electric crystal holder arranged to detachably engage said mounting, said piezo electric crystal holder having means for hermetically sealing a piezo electric crystal 100 therein and means whereby said piezo electric crystal holder may be mechanically supported by said mounting, and an electrical connection established with said piezo electric crystal. 105

4. In a piezo electric crystal apparatus, 110 the combination of a mounting, a piezo electric crystal holder detachably secured to said mounting, a piezo electric crystal carried by said holder, said holder being hermetically sealed and having terminals extending outwardly from within said holder 115 for establishing electrical connection with said mounting when said crystal holder is engaged with said mounting.

5. A piezo electric crystal apparatus comprising in combination a supporting member, a piezo electric crystal holder carried by said supporting member, a piezo electric crystal disposed within said holder and electrically connected with opposite ends of said holder, and means whereby said piezo electric crystal may be electrically connected in a circuit established through contacts on said supporting member when said holder is engaged with said supporting member. 120 125

6. In a piezo electric crystal apparatus, 130

- the combination of a supporting mounting, a piezo electric crystal holder carried by said mounting and detachably engaged therewith, said piezo electric crystal holder comprising a conductive end plate, a housing rising vertically therefrom, and a hermetic closure at the opposite end of said housing, said conductive plate being arranged to support a piezo electric crystal thereon, and means positioned between one face of said piezo electric crystal and the hermetic closure on said housing for establishing electrical connection with said piezo electric crystal, said means extending through said hermetic closure and providing a terminal on the exterior of said housing for electrically connecting said piezo electric crystal in an electrical circuit.
7. A piezo electric crystal apparatus comprising in combination, a mounting adapted to receive one of a plurality of interchangeable piezo electric crystal holders, means for guiding said piezo electric crystal holder into said mounting and for establishing electrical connection with the piezo electric crystal carried by said holder, whereby piezo electric crystals of different frequency characteristics may be readily inserted or removed from an electrical control circuit.
8. In a piezo electric crystal apparatus, the combination of a mounting for piezo electric crystals, a hermetically sealed closure arranged to be readily attached to or removed from said mounting, a piezo electric crystal carried within said closure, said piezo electric crystal having its opposite sides connected to terminals which extend through opposite ends of said closure, whereby said terminals may be electrically engaged with contacts carried by said mounting for establishing a detachable connection between circuits connected with contacts on said mounting and opposite sides of said piezo electric crystal.
9. A piezo electric crystal apparatus comprising in combination a support, a plurality of piezo electric crystal holders each containing piezo electric crystals of differing frequency characteristics, means interior of each of said crystal holders for supporting a piezo electric crystal therein in a manner in which the piezo electric crystal is free to vibrate in its own natural period, connections forming terminals on the exterior of said piezo electric crystal holders providing electrical connections with the opposite faces of each of said piezo electric crystals, and contacts on said support for establishing connection with the terminals of said piezo electric crystal holders whereby piezo electric crystals of different frequency characteristics may be readily interchanged on said support and connections established with the terminals thereof.
10. A piezo electric crystal apparatus

comprising in combination a supporting member, electrical contacts carried thereby, a piezo electric crystal holder arranged to be detachably secured to said supporting member and establish electrical connection with said contacts, said piezo electric crystal holder having a conductive end plate, means for supporting a piezo electric crystal of a particular frequency characteristic upon said conductive end plate, a conductive member arranged to contact with the upper surface of said piezo electric crystal, a vertically extending pin centrally positioned on said conductive member, a guide member surrounding said pin member and spaced from said conductive plate for a distance less than the thickness of said crystal for preventing said crystal from escaping from said supporting means under conditions of abrupt vibration.

11. A piezo electric crystal holder comprising in combination a conductive end plate, a housing secured thereto, a closure for said housing opposite to the end closed by said conductive end plate, said end plate having means for supporting a piezo electric crystal of a particular frequency characteristic in laterally spaced relation within said housing, a metallic plate resting on one face of said piezo electric crystal, a pin centrally positioned on said metallic plate, guide means extending from the end closure and embracing said pin, said guide means being spaced from said metallic plate for a distance less than the thickness of said crystal for preventing said crystal from escaping from said supporting means under conditions of abrupt vibration.

12. A piezo electric crystal holder comprising in combination a conductive end plate, a housing extending from said end plate, a hermetic closure for said housing, a terminal member extending through said hermetic closure, a U-shaped strip secured to the inner extremity of said terminal member, with the sides of said strip arranged in planes substantially perpendicular to the axis of said crystal holder, means carried by the inner side of said conductive end plate for centrally locating a piezo electric crystal within said holder, a conductive plate resting on the upper surface of said piezo electric crystal, a pin centrally positioned on said conductive plate and extending through one side of said U-shaped strip, said U-shaped strip overlying said conductive plate for preventing the piezo electric crystal in said holder from escaping from said means under conditions of abrupt vibration.

13. A piezo electric crystal holder comprising in combination a hermetically sealed closure and means within said closure for securing a piezo electric crystal therein and establishing electrical connection therewith,

while permitting the free vibration of said piezo electric crystal with substantially no restriction.

14. A piezo electric crystal holder comprising in combination a hermetically sealed container, a piezo electric crystal centrally positioned in said container and resilient means for establishing electrical connection with said piezo electric crystal within said container for permitting the free mechanical vibration thereof with substantially no restriction.

15. A receptacle for housing a piezo electric crystal, comprising a casing, a terminal at each end of said casing, a piezo electric crystal mounted within said casing, and con-

nctions between each of said terminals and opposite faces of said piezo electric crystal for enabling said crystal to be connected in an electrical circuit, the walls of said receptacle being spaced from at least two sides of said piezo electric crystal.

16. A receptacle for a piezo electric crystal, comprising in combination a container, an element capable of mechanical vibration mounted within said container, and terminals on opposite ends of said container and connected with opposite faces of said element, said element being spaced from one side of said container for permitting the free mechanical vibration thereof.

ALFRED CROSSLEY.

DISCLAIMER

1,572,773.—*Alfred Crossley*, Washington, D. C. PIEZO-ELECTRIC-CRYSTAL APPARATUS. Patent dated February 9, 1926. Disclaimer filed May 5, 1933, by the assignee, *Wired Radio, Inc.*

Hereby enters a disclaimer to claims 5, 7, 9, 13, 14, 15, and 16 of said patent, which are in the following words, to wit:

“5. A piezo electric crystal apparatus comprising in combination a supporting member, a piezo electric crystal holder carried by said supporting member, a piezo electric crystal disposed within said holder and electrically connected with opposite ends of said holder, and means whereby said piezo electric crystal may be electrically connected in a circuit established through contacts on said supporting member when said holder is engaged with said supporting member.”

“7. A piezo electric crystal apparatus comprising in combination, a mounting adapted to receive one of a plurality of interchangeable piezo electric crystal holders, means for guiding said piezo electric crystal holder into said mounting and for establishing electrical connection with the piezo electric crystal carried by said holder, whereby piezo electric crystals of different frequency characteristics may be readily inserted or removed from an electrical control circuit.”

“9. A piezo electric crystal apparatus comprising in combination a support, a plurality of piezo electric crystal holders each containing piezo electric crystals of differing frequency characteristics, means interior of each of said crystal holders for supporting a piezo electric crystal therein in a manner in which the piezo electric crystal is free to vibrate in its own natural period, connections forming terminals on the exterior of said piezo electric crystal holders providing electrical connections with the opposite faces of each of said piezo electric crystals, and contacts on said support for establishing connection with the terminals of said piezo electric crystal holders whereby piezo electric crystals of different frequency characteristics may be readily interchanged on said support and connections established with the terminals thereof.”

“13. A piezo electric crystal holder comprising in combination a hermetically sealed closure and means within said closure for securing a piezo electric crystal therein and establishing electrical connection therewith, while permitting the free vibration of said piezo electric crystal with substantially no restriction.

“14. A piezo electric crystal holder comprising in combination a hermetically sealed container, a piezo electric crystal centrally positioned in said container and resilient means for establishing electrical connection with said piezo electric crystal within said container for permitting the free mechanical vibration thereof with substantially no restriction.

“15. A receptacle for housing a piezo electric crystal, comprising a casing, a terminal at each end of said casing, a piezo electric crystal mounted within said casing, and connections between each of said terminals and opposite faces of said piezo electric crystal for enabling said crystal to be connected in an electrical circuit, the walls of said receptacle being spaced from at least two sides of said piezo electric crystal.

“16. A receptacle for a piezo electric crystal, comprising in combination a container, an element capable of mechanical vibration mounted within said container, and terminals on opposite ends of said container and connected with opposite faces of said element, said element being spaced from one side of said container for permitting the free mechanical vibration thereof.”
